Inventor

United States Patent Office.

F. W. BROCKSIEPER, OF NEW HAVEN, CONNECTICUT, ASSIGNOR TO SARGENT AND COMPANY, OF SAME PLACE.

Design No. 3,028, dated May 12, 1868.

DESIGN FOR A BRACKET.

The Schedule referred to in these Letters Patent and making part of the same.

TO ALL WHOM IT MAY CONCERN:

Be it known that I, F. W. BROCKSIEPER, of New Haven, in the county of New Haven, and State of Connecticut, have invented a new Design for a Bracket; and I do hereby declare the following, when taken in connection with the accompanying drawings, to be a full, clear, and exact description of the same, and which said drawings constitute part of this specification, and represent, in—

Figure 1, a perspective view, and in

Figure 2 the shelf.

This invention relates to a design for a wall-bracket formed from cast metal, in imitation of carved wood, the base or back being an oak-branch extending up above the shelf, as a means of support for the shelf, and beneath the shelf a second branch springs forward as a brace to support the shelf, all as fully shown in the accompanying illustrations.

Having described my invention, what I claim as new, and desire to secure by Letters Patent, is—

The design for a bracket, as herein described and illustrated.

F. W. BROCKSIEPER.

Witnesses:

J. H. SHUMWAY,

A. J. TIBBETS.
